(57) **CLAIM**

The ornamental design for a notebook computer storage combination including an accessory bag, a cover and a sleeve, as shown.

DESCRIPTION

FIG. 1 is a perspective view of a notebook computer storage combination including an accessory bag, a cover and a sleeve showing our new design;

FIG. 2 is a perspective view of the accessory bag in FIG. 1, shown separated from the notebook computer storage combination including an accessory bag, a cover and a sleeve; FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view of the cover in FIG. 1, shown separated from the notebook computer storage combination including an accessory bag, a cover and a sleeve;

FIG. 10 is a front view thereof;

FIG. 11 is a rear view thereof;

FIG. 12 is a left side view thereof;

FIG. 13 is a right side view thereof;

FIG. 14 is a top view thereof;

FIG. 15 is a bottom view thereof;

FIG. 16 is a perspective view of the sleeve in FIG. 1, shown separated from the notebook computer storage combination including an accessory bag, a cover and a sleeve;

FIG. 17 is a front view thereof;

FIG. 18 is a rear view thereof;

FIG. 19 is a left side view thereof;

FIG. 20 is a right side view thereof;

FIG. 21 is a top view thereof;

FIG. 22 is a bottom view thereof;

FIG. 23 is a perspective view of FIG. 1 showing the accessory bag separated;

FIG. 24 is a perspective view of the sleeve and cover shown separated from the notebook computer storage combination including an accessory bag, a cover and a sleeve, with the cover in an open position of use; and,

FIG. 25 is a perspective view of FIG. 24 showing the cover separated from the sleeve in an environment of use.
